Application August 27, 1934, Serial No. 741,583

22 Claims. (CL 226—82)

This invention relates to packaging of commodities, such as food materials, in jars, cans, bottles or the like, and has to do particularly with improved apparatus and procedure for the evacuation or displacement of air from within such vessels or containers and the application and sealing of closure caps on the vessels.

The general object of the invention is the provision of a simple and easily operated apparatus which will function with certainty and at a desirable output rate to accomplish the evacuation or displacement of air from within packing vessels and apply and seal closure caps upon them.

A more particular object is the provision of such an apparatus which will occupy but little space and which will require but little power for its operation.

Another object is the provision of such apparatus which is adaptable to the handling of vessels and closure caps of various sizes by virtue of a few very simple adjustments.

Other and further objects and advantages of the invention will be pointed out or indicated hereinafter or will be apparent to one skilled in the art upon an understanding of the invention or its employment in use.

For aid in explaining the character of the invention, I illustrate in the accompanying drawings forming a part of this specification, and hereinafter described, certain forms of apparatus in which it may be embodied and practiced, but it is to be understood that these are presented merely by way of illustration, and are not to be interpreted in any fashion calculated to limit the claims short of the true and most comprehensive scope of the invention in the art.

In said drawings,

Fig. 1 is a longitudinal elevational view of a portion of a machine embodying the invention; Fig. 2 is a perspective elevational view of such machine;

Fig. 3 is a transverse elevational view on substantially line 3—3 of Fig. 1;

Fig. 4 is a top or plan view;

Fig. 5 is a side elevational view of a form of driving mechanism which may be employed for operation of the machine;

Fig. 6 is a side elevational detail illustrating the cap-applying means on a larger scale; and

Fig. 7 is a sectional elevational detail of a modified form of sealing head.

Described generally the invention provides an apparatus which includes a housing or chamber in which an atmosphere of hot condensable vapor

of such vapor thereinto, and in which chamber is housed a sealing device which is operable to seat or seal an appropriate closure cap on a vessel. This housing or chamber is open at one end, and between the open end and sealing device is disposed a cap-applying device adapted to position closure caps for application to the vessels incident to movement of the latter to the sealing position under the sealing device. Means is provided for moving vessels into the steam chamber and past the closure-applying device, where closure caps are applied to them, and to sealing position under the sealing device, and then withdrawing the vessels from the steam chamber by movement in a direction opposite to that in which they were introduced. Means is provided for actuating the sealing device to seal the closure caps on the vessels at the sealing station, and to remove the closure-applying device from the path of the sealed vessels so that they may pass without interference during their return from the sealing station.

The invention will be understood in more detail with reference to the illustrative embodiments shown in the drawings, which will now be described. The reference numeral 10 designates various parts of a frame upon which the apparatus is supported. On this frame is fixed a hollow upright standard 11, and a housing member 12 is guided on the standard 11 for vertical sliding movement. The housing member has a top portion 12a and depending parallel side walls 12b, and the top is provided with an aperture at 12c. Hinged at 14 on the top wall is a rocking frame 15 which carries a cover member 16 that has portions extending into the aperture 12c in a manner such as substantially to close the same. The cover member carries a pair of rails 17 which are arranged in parallel relationship to form a cap chute that extends into the housing through the aperture 12c, the upper portion of said rails extending above the cover member for the reception of closure caps which may slide down the rails in single file. At the lower end of one of the rails is a spring pressed detent 18 which engages the lowermost cap so as to hold it on the chute but in a sloping position in which the forward portion of the cap extends beyond and below the lower end of the rails. In association with the lower end of the rails is a cap-leveling device 19, which is supported on the cover member. This detent and cap-leveling device may be of the type which is illustrated in fuller detail in U. S. Patent No. 2,041,891, issued May 26, 1936 to my assignee, White Cap Company.

Guided for vertical reciprocation in a bearing 20 is a sealing plunger 21 which carries at its lower end a sealing head 22 which has passages therein for circulation of a cooling fluid. Tubes 5 24 (see Figs. 2 and 4) are mounted in the sealing head and communicate with its passages, said tubes extending slidably through apertures in the top 12a, one of them being connected with a source of fluid supply by a flexible tube 25, and 10 the other to a point of discharge by a flexible tube 25'.

A rod 26 is mounted for reciprocation in the standard 11, and at its upper end is connected to a yoke member 27. On the upper end of the 15 standard 11 is fixed a bracket 28 on which is hinged a lever 29 having one end engaged in the yoke 27 and the other end hinged to a sleeve 30. The upper portion of the sealing plunger 27 is threaded, and on it are screwed adjusting nuts 20 31 and 32 between which is a sleeve 34 that is slidable on the plunger. A spring 35 is interposed between the lower end of the sleeve 30 and the lower adjusting nut 31. Upward movement of the rod 26 lifts yoke 27 and swings lever 29, 25 thereby moving plunger 27 and sealing head 22 downwardly through the medium of spring 35, which is relatively stiff. After such operation of the sealing head 22, the parts are restored by the reaction of spring 36 which is interposed between bracket 28 and a collar 37 on rod 26. The 30 rod 26 may be operated by treadle mechanism 38, as illustrated in Fig. 2.

The sides 12b of the housing depend in close association with the sides of a table 39 which 35 extends from below the sealing head 22 to a point outside the open end of the housing. On this table is mounted and guided a feeding slide 40, which may be reciprocated longitudinally of the table. The feeding slide has a handle 41 at its 40 rearward end and adjacent its forward end carries a vessel positioning member 42. On the feeding slide is mounted a positioning slide 44, which has a hand engageable portion 45 at its rearward end and a positioning member 46 at its forward end. This positioning slide is reciprocable longitudinally on the feeding slide and is urged to its forward position by a light spring 47. The positioning members 42 and 46 are adapted to engage a packing vessel between them, 45 and hold it on the longitudinal axis of the table, which axis is on the longitudinal median line of the cap chute and sealing head 22. Hence, when 50 a vessel is set upon the feeding slide and engaged by the members 42 and 46, it may be moved into 55 the housing, and past the lower end of the cap chute, to a position below the sealing head 22, by forward movement of the feeding slide on the table. This movement may be imparted by hand, through the medium of the handle 41. As the 60 vessel passes the lower end of the cap chute, it engages the depending portion of the lowermost cap supported thereon and withdraws the cap from the spring detent means, the cap-leveling device 19 operating to level the cap in proper 65 position on the vessel as it passes thereunder to the sealing station below the sealing head 22.

After the operation of the sealing head as above described, whereby the closure cap is seated and sealed on the vessel, the sealed vessel may be 70 withdrawn from the sealing chamber by drawing the feeding slide 40 outwardly. To permit this, means is provided for removing the cap-applying device (which includes the cap-leveling device 19) from the path of the sealed vessel. The 75 means for accomplishing this is as follows: At

48 on the machine frame is rotatably mounted a squared shaft 49 which fits slidably in a bushing 50 that is rotatably mounted in an extension of the housing member 12. The bushing 50 carries a crank arm 51 (Fig. 4) to which is hinged 5 a lifter rod 52. The rearward portion of lifter rod 52 rides on a roller 54 which is coaxial with the hinge of rocking frame 15, and a roller 55, which is journaled on the rocking frame at a point ahead of roller 54, rides on lifter rod 52. 10 As seen in Figs. 1 and 2, lifter rod is offset vertically adjacent its rearward end, to form an incline for cooperation with roller 55.

A crank arm 56 is fixed on shaft 49, and to its outer end is hinged a thrust rod 57, which extends rearwardly alongside the casing wall and has its rearward end 57a turned inwardly to lie in the path of a pair of lugs 58 and 59 which are carried on feeding slide 40. Disposal of said lugs is such that as the feeding slide is completing its 15 inward movement, after the vessel has passed the cap-applying device and is reaching the sealing station, lug 58 will contact rod portion 57a, and incident to the remainder of the forward movement of the feeding slide, will thrust the rod 57 20 forwardly, swinging crank arm 56 and rotating square shaft 49. Such rotation of shaft 49 will rotate bushing 50 and draw lifting rod 52 forwardly, causing its incline to travel on roller 55, and thus rock rocking frame 15 to lift the forward 25 end of cover member 16 and elevate the cap-applying device to a position clear of the return path of the sealed container.

Incident to the return or outward movement of feeding slide 40 whereby the sealed container 35 is withdrawn from the housing, lug 59 engages rod portion 57a and draws thrust rod 57 rearwardly, thus restoring lifter rod 52 and permitting rocking frame 15 and the cap-applying device carried thereby to resume their lowered 40 positions.

When the feeding slide 40 has thus been operated to withdraw the sealed container from the chamber, the positioning slide 44 may be retracted by hand, to permit removal of the sealed container and substitution of an open one. Or, such operation of the positioning slide may be effected automatically through the medium of a bell crank lever 60 which is hinged on slide 40 45 in position such that one arm may cooperate with portion 45 and the other arm with an abutment member 61 which projects upwardly from the side of table 39.

To provide an atmosphere of hot condensable vapor in the sealing chamber, particularly in the upper portion which is traversed by the mouth portion of the vessel, hot steam may be introduced into the upper portion of the housing in a suitable fashion. As illustrated in Figs. 1 and 3 the rearward portion of the housing top may be 60 hollow as indicated at 62, and passages 64 provided leading to a series of ports 65 which open into the upper portion of the chamber. Steam from a suitable source is supplied through a pipe 66 at a continuous rate adequate to maintain 65 the upper portion of the chamber filled with hot condensable vapor.

To accommodate the apparatus to vessels of different heights and to vessels and closures of different diameters, simple adjustments are provided. The spacing of the chute rails 17 may be varied by operation of an adjusting screw 67 (see Fig. 4), which moves them toward or from each other in equal increments. The form and arrangement of the positioning members 42 and 75

46, and the diameter of the sealing head 22 are such as to accommodate and properly cooperate with vessels of different diameters. The housing, and all parts carried thereby, may be adjusted to various elevations in respect to table 39 by operation of a nut 69 which is rotatably journaled on an extension of the housing and threaded on a stationary screw post 70 mounted on the frame, the rotation of the nut being accomplished by operation of a crank 71 which has beveled gear connection with the nut. Incident to such change in the elevation of the housing a corresponding adjustment of nuts 31 and 32 on sealing plunger 21 is made.

15 Reference has been made above to operation of the machine manually, as by hand operation of the slides and foot operation of the treadle. The machine also may be equipped for mechanical operation which is cyclical and automatic. Such an operating means is illustrated in Fig. 5 and includes a motor or other suitable power source 75 which drives a pulley 76 that actuates a worm 77 which drives the worm gear 78 affixed to a cam shaft 79. This cam shaft 25 carries a slide operating cam 80 adapted to actuate a lever 81 that is connected to a lever 82 having connection with the feeding slide 40. Cam shaft 79 carries sealing cam 84 which is adapted to actuate a thrust rod 85 which is connected by a lever 86 with rod 26. The effect of feeding cam 80 is to move slide 40 outwardly or rearwardly and control its return by a spring 87. In such mechanical operation of the machine, operation of positioning slide 44 is accomplished automatically through the medium of lever 60 and abutment member 61, together with spring 47. The relative rotational positions of cams 80 and 84 are such as to effect operation of the sealing head 22 after the vessel has reached the proper 30 position thereunder, and to elevate the sealing head before the feeding slide is moved rearwardly to withdraw the vessel. The form of feeding cam 80 is such as to allow the slide 40 a rest period in its extreme rearward position, to permit removal of the sealed package and substitution of an open container, and also to allow the slide a rest period at its forwardmost position during operation of the sealing head.

The operation of various parts of the apparatus having been described above, I will now describe the operations in their proper sequence, as accomplished for the sealing of successive packages. A suitable supply of hot dry steam is maintained through pipe 66, so that the upper portion of the sealing chamber is kept filled with the hot vapor which is emitted through the ports 65. Appropriate closure caps are placed on the chute rails 17, down which they slide until the lowermost is within the sealing chamber, in substantially the position designated in dotted lines C in Fig. 1, where it is retained by the spring pressed detent. The feeding slide 40 being in its rearward or outermost position, illustrated in Fig. 1, the positioning slide 44 is drawn rearwardly, and a vessel, with its content of material, is placed on slide 40 in engagement with the positioning member 42, approximately in the position shown in dotted profile V in Fig. 1. The feeding slide 40 is then moved forwardly, the 50 positioning slide being released so that its positioning members 46 are moved into contact with the vessel by spring 47, thereby positioning the vessel on the longitudinal axis of the feeding slide. As the vessel is moved forwardly into and through the rearward portion of the sealing chamber, its

open mouth portion travels through the hot vapor atmosphere which is maintained therein, incident to which movement the air within the head space or unfilled portion of the vessel is displaced by the hot vapor. The lowermost cap, which meanwhile has been resting in the hot vapor, has been heated and filled thereby, and as the vessel is moved forwardly, its upper portion contacts the portion of the cap which lies in its path, and withdraws the cap from the retention of the detent, so that the cap comes to rest upon the rim of the vessel, by which it is carried forwardly under the cap-applying device 19, and to a position beneath the sealing head 22. On withdrawal of the lowermost cap the succeeding caps 5 slide down the chute until the lowermost one is arrested by the detent. The vessel reaches a position under the sealing head at the end of the forward movement of the feeding slide. Thereupon the feeding slide remains stationary while the sealing head is moved downwardly to seat and seal the cap on the vessel. Meanwhile a flow of cooling fluid through the cavities in the sealing head has been maintained, thus keeping the sealing head relatively cool. The sealing head 20 is held down on the seated cap for a brief period, with the result that the cap and the vapor within the head space of the vessel are somewhat cooled. This has the effect of reducing pressure within the sealed vessel and preventing the blowing off 25 of the cap. After the vessel has passed the cap-applying device and is moving to sealing position, the rocking frame 15 is rocked to raise the cap-applying device out of the return path of the vessel. Consequently, when the sealing head is 30 elevated, the feeding slide may be immediately withdrawn to move the sealed vessel quickly out of the sealing chamber and to the starting position. Incident to this outward movement of the feeding slide, the rocking frame is rocked to restore the cap-applying device to its lowered position, where it holds the next cap in position for application to another vessel which is positioned 35 on the feeding slide after the sealed one has been removed.

In the operation of the feeding slide by hand, the resistance offered by the means which shifts the cap-applying device imposes a decelerating influence on the slide as it approaches its forward limit position. This tends to prevent a too sudden stopping of the slide. In the mechanically operated mechanism this effect may be obtained by a proper profile of the feeding cam. Types of closure caps which may be employed effectively in apparatus of this type are illustrated in U. S. Patents Nos. 1,590,787 and 1,807,187, but it is to be understood that other types of closure caps may be utilized in it with like results.

From the foregoing it will be seen that the invention may be embodied in a very simple apparatus which requires but little space, and but a small amount of power for its operation. A high degree of vacuum may be obtained in packages sealed in the apparatus above described, as the movement of the open vessel through the hot vapor atmosphere is effective to produce a quite complete displacement of air from the head space, the air being quite thoroughly displaced also from the closure caps preliminary to and during the application of them to the vessels. When the cap is applied and sealed on the vessel, the unfilled space within the package is occupied by the hot vapor, with the result that upon the cooling of the cap under 60 65 70 75

the sealing head and the further cooling after withdrawal from the sealing chamber, the contraction and condensation of the contained vapor results in the reduction of the internal pressure in the package to a point very much below atmospheric pressure. This aids in the secure retention of the closures on the vessels. It is also to be observed that the closing and sealing of the vessels is accomplished under sterilizing conditions in the hot vapor atmosphere.

In the modified form of sealing head illustrated in Fig. 7, the lower face is provided with intersecting radial and annular channels 22a communicating with the interior passages by a port 22b which normally is closed by a valve 23. When the sealing head is pressed into engagement with a closure cap on a vessel therebelow, the stem of the valve is thrust upward, thus unseating the valve and permitting cooling water to flow from the interior passages out onto the cap, for the purpose of cooling it while it is held seated on the vessel by the sealing head.

25 What I claim is:

1. Package sealing apparatus comprising in combination a feeding device operable to move a packing vessel first in a forward direction and then in a reverse direction, a cap-applying device arranged to feed and present closure caps successively in position for application to a succession of vessels in the course of their forward movement by the feeding device, and a sealing device operable to seal the applied cap on each of the successive vessels at the end of its forward movement and before the start of its reverse movement.

2. Package sealing apparatus comprising in combination a sealing device operable to seat a closure cap on a packing vessel, feeding means operable to move a packing vessel to the sealing device in one direction and from the sealing device in an opposite direction, a cap-applying device in the path of movement of the vessel to the sealing device, and shifting means operable to shift the cap-applying device from the path of the vessel prior to its movement from the sealing device.

3. Packaging apparatus as specified in claim 2 and wherein the feeding device comprises a reciprocable slide adapted to support a packing vessel and said shifting means is operated incident to movement of the slide.

4. In packaging apparatus, in combination, a reciprocable feeding member adapted to support a packing vessel and to move the same first in an advancing direction and then in an opposite direction, a cap-applying device and a sealing device arranged over the path of movement of the feeding member for cooperation with a vessel thereon, means for operating the sealing device after completion of the advancing movement of the feeding member, and means for shifting the cap-applying device after the vessel has been advanced past the same.

5. In package sealing apparatus, in combination, a sealing device operable to seat a closure cap on a packing vessel, a reciprocable feeding member operable to move a packing vessel to and from the sealing device, a cap-applying device arranged to support a closure cap in position to engage a vessel while the vessel is moving to the sealing device, and means operable to effect movement of the cap-applying device to-

ward and from the feeding member while the vessel is being moved by the feeding member.

6. In package sealing apparatus, in combination, a sealing device operable to seat a closure cap on a packing vessel, a rocking frame, a cap-applying device supported by said rocking frame for supporting a cap for application to the vessel, feeding means operable to move the packing vessel past the cap-applying device on the way to and from the sealing device, and means for rocking the rocking frame to move the cap-applying device toward and from the path of the vessel while the vessel is being moved by the feeding means. 10

7. Package sealing apparatus comprising in combination a sealing chamber open at one end, a sealing device operable in said chamber, feeding means operable to move a packing vessel into and out of the chamber through the open end thereof, a cap-applying device arranged to apply a cap to a vessel in the course of its movement in the chamber, means for supplying hot vapor to the chamber, and means for cooling the sealing device. 15

8. Package sealing apparatus comprising in combination a sealing chamber open at one end, a sealing device operable in said chamber, a reciprocable feeding member operable to move a packing vessel into and out of said chamber through its open end, a cap-applying device arranged to apply a closure cap to the vessel in the course of its movement in the chamber, and means for supplying hot vapor to the chamber. 20

9. Package sealing apparatus comprising in combination a sealing chamber open at one end and closed at the other, a sealing device in said chamber adjacent the closed end thereof, feeding means operable to move a packing vessel into and out of the chamber through the open end thereof and to a position below the sealing device, a cap-applying device disposed in the chamber between its open end and the sealing device, and means for supplying hot vapor to the sealing chamber. 35

10. Package sealing apparatus as specified in claim 9 and including means operable in conjunction with the feeding means to effect shifting of the cap-applying means toward and from the path of the vessel. 40

11. Package sealing apparatus comprising in combination a sealing device, a reciprocable slide operable to move a packing vessel to and from the sealing device, a cap-applying device arranged for cooperation with a packing vessel in the course of its movement to the sealing device, and means operable from the slide for shifting the cap-applying device. 50

12. In package sealing apparatus, in combination, a cap-applying device, a reciprocable slide operable to move a packing vessel forwardly and rearwardly past the cap-applying device, positioning members carried by the slide for cooperation with the packing vessel to hold the same, and means operable incident to movement of the slide for shifting one of said positioning members 60 to free the vessel at the end of its rearward movement. 65

13. In packing apparatus, in combination, a sealing chamber having an aperture through its top, a shiftable cover member substantially closing said aperture in its different positions, a cap-applying device carried by said cover member and disposed within the chamber, feeding means for moving a packing vessel in the chamber and past the cap-applying device, and means for shifting 70 75

the cover member incident to movement of the feeding means.

14. Package sealing apparatus as specified in claim 13 and including means for supplying hot vapor into the sealing chamber.

15. In package sealing apparatus, in combination, a sealing chamber having a top aperture, feeding means for moving packing vessels in said chamber and past said aperture, a shiftable cover member substantially closing said aperture, and a cap chute carried by said cover member and extending through said aperture.

16. Package sealing apparatus comprising in combination a sealing device operable to seal a closure cap on a packing vessel, reciprocable feeding means operable to move a packing vessel to and from said sealing device, a cap chute arranged for cooperation with a vessel in the course of its movement to the sealing device, and means operable in conjunction with the feeding means for shifting said cap chute.

17. In package sealing apparatus, in combination, feeding means for moving a packing vessel first in one direction and then in another direction, a shiftable cap chute arranged to support a plurality of closure caps above the path of the feeding means, and means operable to shift said cap chute toward and from the feeding means incident to movement of the feeding means in respective directions.

18. In package sealing apparatus, in combination, reciprocable feeding means operable to transport a packing vessel to and fro, a rockingly mounted cap chute arranged to support a plurality of closure caps above the path of the feeding means, and means for rocking the cap chute to elevated position after the vessel has passed it in one direction and to lowered position after the vessel has passed it in the opposite direction.

19. In package sealing apparatus, in combination, feeding means operable to move packing vessels successively in opposite directions on a straight path, and cap-applying means adapted to support closure caps for application to packing

vessels in the course of their movement by the feeding means and operable to move closure caps into and out of the path of the vessels incident to their movements in respective directions.

20. In package sealing apparatus, in combination, a sealing chamber, means for supplying hot vapor thereinto, a sealing device in said chamber and having fluid passages, means for conducting cooling fluid from externally of said chamber to said passages and from said passages to a point exterior of said chamber, and feeding means for moving packing vessels into said chamber and to said sealing device and from said sealing device out of said chamber.

21. In a package sealing apparatus, in combination, a sealing chamber, means for supplying hot vapor thereinto, a sealing head in said chamber and having interior fluid passages, means for pressing said sealing head into engagement with a closure cap on a vessel therebelow, means for conducting cooling fluid to said passages from externally of the sealing chamber, said sealing head being provided with an outlet for conducting fluid from its interior passages into contact with a closure cap in engagement with the sealing head, and a valve normally closing said outlet and operable to open same incident to movement of the sealing head into engagement with the closure cap.

22. In package sealing apparatus, in combination, a sealing head having an interior passage, means for pressing said sealing head into engagement with a closure cap on a vessel therebelow, means for conducting cooling fluid to the interior passage of the sealing head, said sealing head being provided with an outlet for conducting fluid from its interior passage into contact with a closure cap in engagement with the sealing head, and a valve normally closing said outlet and operable to open same incident to movement of the sealing head into engagement with the closure cap.

GEORGE P. WHITE.
